UNITED STATES PATENT OFFICE.

JONAS CARNIE TOUCHSTONE AND JAMES MONROE WORTHINGTON, OF
LOVELADY, TEXAS.

QUILTING-FRAME FOR SEWING-MACHINES.

SPECIFICATION forming part of Letters Patent No. 436,508, dated September 16, 1890.

Application filed March 4, 1890. Serial No. 342,589. (No model.)

To all whom it may concern:

Be it known that we, JONAS CARNIE TOUCHSTONE and JAMES MONROE WORTHINGTON, citizens of the United States, residing at Lovelady, in the county of Houston and State of Texas, have invented certain new and useful Improvements in Quilting-Frames; and we do declare the following to be a full, clear, and exact description of the invention, such as will enable others skilled in the art to which it appertains to make and use the same, reference being had to the accompanying drawing, and to the letters of reference marked thereon, which form a part of this specification.

The object of our invention is to combine the parts by which a quilter is suspended from a ceiling and connected with a sewing-machine, as hereinafter described, and pointed out in the claim.

The drawing is an elevation in perspective.

A represents the ceiling, from which, by means of the wires B B, I suspend the track C on an incline. The end wires B B are placed about three feet apart at the ceiling and above each end of the track C, to prevent the latter from vibrating while the quilting is being done. The track C has its bevel side facing the sewing-machine, and is supported as well as steadied by the beam D, which is fastened adjustably to a sewing-machine arm V by means of the buckle-straps X X, attached to the piece E.

H H are grooved wheels arranged on a head-block F, so as to face arm V, while the said head-block itself passes on the opposite side of the track C from the said arm V, thus enabling the operator to keep the wheels on the track and to permit the head-block to pass the beam D. The wheels H are screwed to the block G, which forms the top of the head-block F and is in a perpendicular line with the block I, attached to the lower end of said head-block. Through the block I and the middle of suspension-rod L passes the swiveled bolt J, carrying at its lower end the nut K. By this arrangement the quilting-frame hangs perpendicularly and the head-block is clear of the side of the track, so as to avoid

all unnecessary friction. The track C is arranged with respect to the head-block and sewing-machine so as to occupy an intermediate position.

L is a suspension-rod provided with metallic clasps n n at each end, and through these clasps pass the top ends of the uprights m m. The rod L can thus be slid up and down, so as to adjust the quilting-frame to the height of the sewing-machine, being held at any adjustment by the thumb-screws y y. On the lower ends of the uprights m m are also the clasps o o, through which pass the end plates of the frame P, said end plates sliding through the clasps and having end slots p. The circular motion given to the frame by the swivel-bolt J and the vibrating motion, from being under the track, are preserved, while a free and easy motion in all directions is maintained. The quilting-rod R R are held in place by the perforated wheels s and screw-hooks t. As the track C is suspended with an incline and bead on top for the wheels H to run on, a self-feed is given to the frame as it passes over the top of the sewing-machine.

Having thus described all that is necessary to a full understanding of our invention, what we claim as new, and desire to protect by Letters Patent, is—

The track C, having a bead on the inner side of top, an eye at each end, and suspended on an incline from the ceiling by two wires B B at each end, said wires diverging from the track-eyes to the ceiling, in combination with the head-block F, arranged on the opposite side of track C from the sewing-machine arm and carrying rolls H H, suspended from a block G, the quilting-frame swiveled at J to the head-block F, and the beam D, connected with the track C and with the sewing-machine arm, as described.

In testimony whereof we affix our signatures in presence of two witnesses.

JONAS CARNIE TOUCHSTONE.

JAMES MONROE WORTHINGTON.
